TELESCOPE MOUNT

John C. Garand, Springfield, Mass., assignor to
the United States of America as represented
by the Secretary of War

Application June 1, 1945, Serial No. 597,052

3 Claims. (Cl. 33—50)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to improvements in firearms and is directed more particularly to an improved means whereby a telescopic sight may be mounted thereon.

This invention is especially adapted for use in association with a shoulder rifle, such as the U. S. Rifle Cal. .30, M1, and accordingly, the showing and description will apply to such a combination, but it is to be understood that the novel features of the invention are not to be restricted thereto.

It is a particular object of the invention to provide a telescopic sight mount which may be rigidly associated with the firearm and as a special feature there is provided novel means whereby the mount is easily assembled or disassembled. It has been a problem in military service to provide a sight mount which is easy to clean or repair in case of injury thereto and it has been a common objection to mounts heretofore known that they become clogged with dirt or other foreign matter and are thereupon rendered unfit for service or at least incapable of quick removal from or assembly to the firearm, as is desirable for obvious purpose.

Furthermore, it is an essential requirement for all removable telescopic sight mounts that they assemble each time in identical relationship to the firearm so as to eliminate any necessity for re-targeting the weapon upon reassembly of the telescope thereon.

It is accordingly the principal object of this invention to provide a sight-mounting construction which may be readily removed and replaced as often as is necessary, with a reasonable guarantee that the sight will be positioned in the same location relative to the barrel. That is to say, the arrangement is such that the operator of the firearm is assured of accurately replacing the sight with respect to the longitudinal axis of the barrel without difficulty.

The specific nature of the invention as well as other objects and advantages thereof will clearly appear from a description of a preferred embodiment as shown in the accompanying drawings in which:

2

Fig. 1 is a side elevational view of a telescope assembled to a firearm by means of a mount in accordance with this invention.

Fig. 2 is a sectional view of the sight mount of Fig. 1, taken along the plane 3—3.

Fig. 3 is a front elevational view of the base member of the improved sight mount.

Fig. 4 is a side view of the base member.

Fig. 5 is a side elevational view of the sight mount, taken from the side opposite to Fig. 1.

Fig. 6 is a side elevational view of a telescope assembled to a firearm by means of a second modification mount constructed in accordance with this invention.

15 Fig. 7 is a front elevational view of the modified mount shown in Fig. 6.

Fig. 8 is a side elevational view of the modified sight mount taken from the side opposite Fig. 6.

20 In Figs. 1 and 2 there are partially shown conventional elements of a firearm including a telescope 1, a barrel 2, receiver 4, and handguard or stock member 8. This assembly is shown for purposes of description only, and as will be understood, it does not form any part of the invention. The handguard 8 surrounds the barrel 2 but terminates forwardly of the receiver so as to provide a convenient space for mounting to the firearm an element 10 which may be referred to as

30 a sight base.

The base 10 comprises a generally semi-cylindrical member having exterior planar side and top surfaces 24 and 26 respectively. For purposes of strengthening the construction, it is desirable that the side plate portion 24 and top plate portion 26 be of substantial thickness.

The interior, semi-cylindrical surface 11 of the base 10 is shaped to snugly surround the barrel 2. An inwardly projecting tooth 12 is provided

40 on base 10 which engages in one of a pair of longitudinal grooves 7 conventionally provided on the side of the barrel to initially position the sight base in proper angular relation to the barrel 2. A transverse hole 13 is provided in base 10 passing thru side surface 24. Utilizing the

45 hole 13 as a jig, an extension hole 5 is drilled into barrel 2. Permanent, rigid assembly of the sight base 10 to the barrel 2 is then accomplished by driving a dowel pin 14 into holes 13 and 5 and 50 then expanding the dowel pin 14.

The top and bottom edges of side surface 24 are formed to provide beveled surfaces 29 and 30 respectively. A threaded transverse opening 22 is also provided centrally in side plate portion 24 of base 10 which communicates with a vertical opening 25 which extends thru the top plate portion 26. The opening 25 facilitates the cleaning of the threads of threaded hole 22.

A bracket member 40 is provided to mount the telescope 1 to the base 10. The bracket member comprises a semi-cylindrical scope securing portion 41 integrally formed with a depending mounting portion 42.

The top edge of scope securing portion 41 has integrally formed thereon a plurality of spaced hinge brackets 43. A cooperating, semi-cylindrical scope securing portion 44 is provided having integrally formed spaced hinge brackets 45. The two semi-cylindrical scope securing portions 41 and 44 are held in pivotal relationship by a pin 46 which passes through the aligned hinge brackets 43 and 45.

The mounting portion 42 of bracket member 40 is provided at its bottom with projecting, obliquely planar surface 47 which is shaped to cooperate with the bottom beveled surface on the sight base 10. At the top of bracket portion 42 an outwardly projecting web 48 is provided which has a horizontal bottom surface 49 which in assembly engages the planar top surface 26 of the sight base 10.

Two spaced, raised bearing surfaces 50 are also provided on the face of mounting portion 42 which lies adjacent the sight base 10 and these bearing surfaces engage the planar side surface 24 of the sight base. The projecting beveled surface 47 on the mounting portion 42 is preferably located centrally with respect to the raised surface 50 so as to provide three-point locating contact between mounting portion 42 of the bracket member and the sight base 10. It will be noted that a tri-plane contact is provided between bracket member 40 and base 10, thus insuring the identical angular positioning of bracket member 40 with respect to the firearm in each assembly.

The bracket member 40 may be assembled to the sight base 10 without removing the hand-guard 8 by bringing the mounting portion 42 into abutting engagement with the base 10. The bracket member 40 is secured in identical longitudinal position on sight base 10 in each assembly by means of a bolt 52 which passes through a central hole 53 in mounting portion 42 and threadably engages the horizontal threaded hole 22 in sight base 10.

An enlarged cylindrical knob portion 54 is suitably secured to the outwardly projecting end of bolt 52. The periphery of knob 54 is provided with serrations 55 to permit the manual application of a substantial rotative force to the bolt 52, thus drawing the bracket member 40 tightly against the sight base 10. A dish-like washer 56 is preferably provided between operating knob 54 and the adjacent surface of mounting portion 42.

If desired, the serrations 55 may be extended to the vertical surface 57 of the knob 54 which lies adjacent the mounting portion 42 and a detent 58 provided having a cylindrical body portion 64 press fitted in a suitable hole in mounting portion 42. Detent 58 cooperates with such serrations and thus provides a lock for the bolt 52.

The telescope 1 is secured to the mount by insertion thereof between the two semi-cylindri-

cal scope securing portions 41 and 44 and these portions are then brought into tight engagement with the telescope by means of screws 59.

An alternative construction of the bracket member 40 is disclosed in Figs. 6, 7 and 8. In this construction the scope securing portion 60 is formed entirely in one piece with mounting portion 42. Scope securing portion 60 comprises a cylindrical member which is split at its base as indicated at 61. The telescope 1 is inserted within the cylindrical bore 62 defined by the scope securing portion 60 and is rigidly secured therein by means of screws 63 which pass through the split portion 61 of member 60 and when tightened reduce the diameter of the scope receiving bore 62. The mounting portion 42 of this modification is substantially identical to that previously described and cooperates in the same manner with the sight base 10 with the exception that two spaced oblique bearing surfaces 51 are provided to cooperate with surface 47 of the sight base.

It is thus apparent that this invention provides an extremely simple telescope sight mount which is particularly adaptable to military application. The mount may be applied to any gun in the field inasmuch as only the simplest of tools are required for its application to the firearm. Furthermore, the bracket portion of the sight mount may be quickly assembled and disassembled from the gun and with each assembly it is assured that the mount will assume an identical position.

I claim:

1. In a firearm, in combination, a barrel having a longitudinal groove therein, a sight base having a substantially semi-cylindrical concave surface shaped to snugly engage said barrel, an inwardly projecting tooth on said sight base engageable in said barrel groove to angularly position said sight base thereon, said sight base having a transverse hole therethrough whereby an aligned hole may be produced in said barrel by utilizing said transverse hole as a jig, and an expanded dowel pin communicating between said aligned holes.

2. The combination defined in claim 1 wherein said sight base has a plurality of exterior, planar bearing surfaces, each parallel to the barrel axis when assembled thereto and respectively disposed in a horizontal, a vertical and an oblique plane, a bracket member including a scope mounting portion arranged to surround and secure a telescope and a depending bracket portion having planar bearing surfaces constructed and arranged to engage said first mentioned bearing surfaces, whereby said bracket member is positioned to said sight base in fixed angular relation, and screw means for securing said bracket member to said sight base.

3. In a firearm having a barrel provided with a transverse recess therein and a longitudinal groove opposed thereto, a telescopic sight mount assembly comprising, a base member having a substantially semi-cylindrical concave surface arranged to snugly engage the barrel, an inwardly projecting tooth on said base member engageable in the groove of the barrel so as to angularly position said base member thereon, said base member being provided with a transverse hole therethrough for aligning with the transverse recess in the barrel and with a trio of exterior planar bearing surfaces, each of said bearing surfaces being parallel to the axis of the barrel but respectively disposed on a horizontal, a vertical and an oblique plane with respect to the

axis of the barrel, an expanded dowel pin communicating between said aligned holes to secure said base member to the barrel, a bracket member having a scope-mounting portion arranged to releasably hold a telescope and a depending bracket portion provided with a plurality of bearing surfaces adapted to engage said trio of bearing surfaces whereby said bracket member is positioned in fixed angular relation to said base member, and screw means for releasably securing said bracket member to said base member.

JOHN C. GARAND.
